UNITED STATES PATENT OFFICE.

HOWARD T. INGHRAM, OF CHICAGO, ILLINOIS.

HOLDING IMPLEMENT.

1,256,565.

Specification of Letters Patent. Patented Feb. 19, 1918.

Application filed March 29, 1917. Serial No. 158,412.

To all whom it may concern:

Be it known that I, HOWARD T. INGHRAM, a citizen of the United States, residing at Chicago, in the county of Cook and State 5 of Illinois, have invented certain new and useful Improvements in Holding Implements, of which the following is a specification.

This invention relates to improvements in 10 devices adapted to hold brushes of various kinds, mopping fabrics, scrubbing, wiping and dusting cloths and similar articles, and has for one of its objects to provide a device of this character in which the various articles to be held may be easily attached and 15 detached and firmly held in position while in use.

Another object of the invention is to provide a device of this character adapted to 20 be adjusted to hold the articles at any required angle relative to a supporting handle.

With these and other objects in view, the invention consists in certain novel features of construction, as hereinafter shown and 25 described and then specifically pointed out in the claim; and in the drawings illustrative of the preferred embodiment of the invention—

Figure 1 is an end elevation of the im- 30 proved device;

Fig. 2 is a rear elevation of the same;

Fig. 3 is a sectional detail illustrating the coupling between the handle and the body 35 of the improved device;

Figs. 4 and 5 represent the blanks from 40 which the head members are constructed;

Fig. 6 is a view of one of the blanks from 45 which the gripping members are constructed;

Fig. 7 is a detached perspective view from 50 above, of one of the gripping members.

Corresponding and like parts are referred 55 to in the following description and indicated in all the views of the drawings by the same reference characters.

The different members of the improved 60 device are mostly compressed from sheet or plate metal, and comprise coacting head portions pivotally united, coacting gripping jaws connected to the head portions, a holding member adjustably coupled to the head portions and adapted to be connected to an operating handle, means for compressing the holding jaws against the object being held, 65 and means for adjusting the holding member and the handle relative to the head por-

tions so that the article being held may be disposed at any required angle relative to the handle.

The blank from which one of the head 60 members is constructed is shown in Fig. 4 and comprises side portions 10 and a connecting web 11. The portions 10 are enlarged at one end substantially circular in shape. The members 10 are bent at right 65 angles to the web portion 11 along the lines 13 so that the portions 10 extend at right angles to the web and in spaced relation to each other. The blank from which the other head member is formed is substantially like 70 the blank shown in Fig. 4 except that it is shorter and includes side members 14 and a connecting web 15, the portions 14 being bent at right angles to the web portion 15 so that the portions 14 are disposed in 75 spaced relation to each other and fit between the side portions 10. At one end the members 14 are substantially circular in shape and pivotally united at 16 between the side portions 10.

Attached to each of the web portions 11 and 15 is a holding device or gripping jaw 80 each formed of a sheet of plate metal bent into the required shape. The gripping members are precisely alike and the description of one will suffice for both. Each gripping member comprises a body portion 17 cut substantially in triangular shape and bent along the dotted line 18 to form a flange 19, and likewise bent along the lines 90 20 to form flanges 21. The flanges 21 are of less length than the sides of the body 17 adjacent thereto so that when the flanges are bent at right angles to the body 17 a 95 space will be left at the apex of the body 17 to receive the web portions 11—15 of the head members. By this means the inner ends of the flanges 21 bear against the sides 10—14 of the head members, while the opposite ends of the flanges 21 are directed in 100 parallel relation to the flange 19 and spaced therefrom. The body portions 17 are riveted or otherwise rigidly secured respectively to the webs 11—15. When thus arranged the flanges 19 are directed toward each other 105 with their free edges in spaced relation, the object to be hereafter explained.

A holding member forms a part of the 110 improved device and comprises a disk 22 circular in shape corresponding to and substantially the same size as the circular portions of the members 10. The member 22

is adapted to be rigidly coupled to the handle portion 23, and for the purpose of illustration the handle engaging portion of the member 23 is in the form of a threaded stud 5 24 engaging in the handle. Preferably the handle is provided with a supporting ferrule 25. A threaded pivot 26 extends through the enlarged portions 10 of the head member and through the holding member 10 22 and is provided with a wing nut 27 so that the members through which the pivot passes may be firmly clamped together to hold them in adjusted position. The enlarged portions 10 and the holding member 15 22 are provided with coacting depressions and projections indicated at 28, to enable the members united by the pivot 26 to be firmly locked together and prevented from displacement. By this arrangement the 20 head members together with the gripping jaws may be disposed at any required angle relative to the handle, and firmly held in adjusted position.

Extending through the web portions 11—25 15 of the head members is a threaded bolt 29 supplied with a wing nut 30, so that the head members together with the gripping jaw members may be firmly compressed toward each other to hold any article which 30 35 may be disposed between the jaws. Preferably a spring indicated at 31 is disposed between the web portions 11—15 of the head member and operates to hold the head members and the gripping jaws normally in open position, and when the wing nut 30 is actuated the jaws will be forced toward each other against the resistance of the spring. The spring thus operates to automatically open the jaws when the wing nut 30 is released.

The improved implement thus constructed may be employed for gripping brushes, mop fabrics, dusting cloths, or other articles, and will firmly hold the article rigidly 45 in position, and by adjusting the head mem-

bers relatively to the holding member, the article may be held in any required angle relative to the handle. When employed for holding a brush, the head portion 32 of the brush will be provided with a holding member 50 55 33 having a T shaped head as shown in Fig. 1, over which the flanges 19 of the head members engage as shown. When thus arranged the flanges 19 engage the inner faces of the T head, while the outer face of the head is engaged by the forward terminals of the flanges 21.

The improved device is simple in construction, can be inexpensively manufactured and all of the parts except the member 60 65 22 pressed from sheet metal, preferably steel.

The improved device is strong and durable, and may be manufactured of any required size to adapt it without material 65 70 structural change to hold articles of various sizes and forms.

Having thus described the invention, what is claimed as new is:

In an implement of the class described, 70 coacting head members each including a connecting web and side portions, means for swingingly uniting said side portions, coacting gripping members connected respectively to said web portions and each having 75 an inwardly directed flange at its forward edge adapted to engage one side of the article to be held and inwardly directed flanges at its side edges adapted to bear at one end against the other side of the article to be 80 held and bearing by their other ends against the side portions of the head members and bracing and supporting the same, a handle connected between the side portions of one of said head members, and means for forcibly moving said gripping members toward each other.

In testimony whereof I affix my signature.

HOWARD T. INGHRAM. [L. S.]
